VENTILATING AND SIGNAL WINDOW
CONSTRUCTIONJohn F. Levan, Elkhart, Ind., assignor to Excel
Curtain Company, Elkhart, Ind., a corporation
of Delaware

Application August 29, 1933, Serial No. 687,339

1 Claim. (Cl. 296—44)

This invention relates to window structures, particularly window structures for motor vehicles, and the like, which are capable of being raised and lowered.

5 It has for its object such a window embodying a sash pivotally mounted on an upright axis to swing laterally into and out of different inclined open positions for the purpose of controlling the ventilation through the window, and also for the 10 purpose of providing an opening for signaling other vehicles through the window, and when in its normal position is capable of being raised and lowered.

It further has for its object, a particularly simple and easily operable mechanism for holding the pivoted sash in any one of its adjusted positions.

It further has for its object, a holding mechanism which is located in a hollow member, or rail, 20 of a main frame, or sash, supporting the pivoted sash, and a holding mechanism of such construction that it can be located in such a confined space, and at the same time be readily operable.

The invention consists in the novel features 25 and in the combinations and constructions hereinafter set forth and claimed.

In describing this invention, reference is had to the accompanying drawing in which like characters designate corresponding parts in all the 30 views.

Figure 1 is a fragmentary elevation of a structure embodying my invention.

Figures 2 and 3 are detailed views of a mechanism for holding the pivoted sash in its adjusted 35 position.

Figure 4 is a sectional view taken on line 4—4, Figure 1.

1 designates a suitable hollow body which may be the door of a motor vehicle, or the portion of 40 the door below the belt, or may be a portion of the vehicle body.

2 is a sash capable of being raised and lowered into and out of the body 1. This sash includes a marginal frame usually formed up of sheet metal 45 having tail pieces 3 extending into the body 1 and coacting with guides therein. The sash is capable of being raised and lowered by any suitable window raising and lowering mechanism.

In the illustrated embodiment the sash 2, in 50 addition to a marginal frame, includes a glass pane 4 which partly fills the space enclosed by the frame 2, the glass pane 4 being here shown as filling substantially the rear half of such space, and also includes a movable sash member 5 filling the remainder, that is, substantially the front

half of such space. The sash member 5 is pivoted on an upright axis to the upper and lower rails of the sash frame 2 in order to swing, from its normal closed position, that is, when it is in the general plane of the sash frame 2, outwardly into different inclined open positions, the pivotal axis being located toward the front edge of the sash member 5 so that when the sash member 5 is swung open, it forms a relatively narrow front inlet air opening, and a wider rear outlet opening. 10

By sash is meant either a glass pane mounted in a frame, or a partial frame, or a glass pane without a sash frame. However, in the illustrated embodiment of my invention, the sash member 5 is provided with a marginal frame 6. The sash member 5 is pivotally mounted in the sash frame 2 by trunnions 7 and 8 projecting from the upper and lower rails of the sash frame 6, these being mounted in suitable bearings in the upper and lower rails 9 and 10 of the sash frame 2. The rear stile of the sash member 5 is also formed with suitable weather stripping for coacting with a muntin 12 at the front end of the glass pane 4, for sealing the joint between the sash member 5 and the glass pane 4 when the sash member 5 is closed. The sash 5 is also provided with a flange 11 on the rear stile or at its rear edge to lap the muntin. 20

By this construction the pivoted, or ventilating window, can be lowered and raised into and out of the body 1. 25

The means for holding the sash member 5 in its normal closed position, and in any one of its adjusted, or angular positions, is located in the bottom rail 10 of the sash 2. This rail 10 is formed up of channel iron with the channel facing upwardly. The means for holding the sash member 5 in position is operable by a handle on the outside of the bottom rail 10, and so located that it can pass up and down through the slot 35 in the upper edge of the body 1 through which the sash frame 2 moves. 40

In the illustrated embodiment of my invention, the locking means includes ratchet mechanism including a part mounted on the lower trunnion 8 within the hollow rail 10, and a part movably mounted in the hollow rail. The part mounted on the trunnion is here shown as a wheel 13 and is preferably a ratchet wheel, or a wheel with comparatively small ratchet teeth 14 capable of permitting ratcheting in both directions, although these parts may be a friction wheel and pawl or their equivalent. However, to effect immediate accurate locating of the sash member 5 in any open position or angle or the step by 50 55

step movement effected by ratchet mechanism is preferable. The part movable in the hollow rail 10 is here shown as a shoe or block 15 spring pressed by a spring 16 against the periphery of 5 the wheel 13 and having ratchet teeth 17 complementary to the teeth 14, the shoe or block having a stem extending lengthwise of the hollow rail 10 about which the spring is coiled, the spring thrusting at one end against an internal 10 abutment 18 within the hollow rail which has a guide opening for the stem, and at its other end against the shoe or block 15. Manually operable means are provided for holding the block or shoe 15 from ratcheting movement and hence, 15 holding or locking the sash 5 in its adjusted position. This means is here shown as a rock shaft 19 extending transversely of the hollow rail 10, and having a cam or eccentric 20 thereon arranged to thrust against the end of the stem. 20 The rock shaft has a handle 21 on the outside of the rail, which handle extends radially relatively to the shaft in order to lie close to the outer face of the rail.

When the sash is raised, and the rock shaft 25 is turned so that the low point of the eccentric or cam is opposite the end of the stem, then the sash member 5 can be turned about its axis as the shoe or block 15 is then free to ratchet. When, however, the rock shaft is turned to carry 30 the high point of the cam or eccentric against the end of the stem, the shoe or block is held from ratcheting movement and hence, the sash member 5 held in its adjusted position.

As here illustrated, the block or shoe 15 and 35 associated parts, that is, the spring and cam, are a self-contained structure insertable as a unit in the rail 10, and suitably secured therein, the insert being a channel 25 in which the block slides, and through which the trunnion 8, with 40 the ratchet wheel thereon, extends, and in which the shoulder 18 is formed, and in which the cam shaft 19 is mounted. The insert is covered by a suitable weather strip 26 coacting with the rail of the sash member 5, the weather strip 45 26 having an opening for a spacer 27 around the trunnion 10 between the lower rail of the sash

member 5 and the insert 25. The spacer 27 is here shown as formed with a recess (Figure 2) in which a spring 28 is located thrusting at one end against the bottom of the recess and at its other end against the insert, the spring taking 5 up looseness and preventing rattle.

The top rail of the sash member 5 is provided with an insert 29 and ratchet mechanism coacting with the trunnion 7, which insert 29 and ratchet mechanism is similar to the insert 25 10 in the bottom rail and the ratchet mechanism therein, except that the ratchet mechanism in the insert 29 has no locking means corresponding to the cam 20 and handle 21.

By this window construction, the pivoted ventilating window can be raised and lowered into and out of the lower body, or vehicle body, and when in its elevated position, the sash member can be locked in its adjusted position against unintentional displacement. Owing to the construction of the ratchet mechanism, and its relation to the sash member 5, or the trunnion thereof, it is particularly compact and can be located in a hollow rail and operable from the outside of the rail by means which does not obstruct the raising and lowering of the sash.

What I claim is:

In a window structure, the combination of a suitable body, a window sash capable of being lowered and raised into and out of the body, the 30 sash including a frame having a hollow rail, a second sash pivotally mounted in the first sash on an upright axis and movable about its axis from normal closed position into different inclined open positions, means for pivotally mounting the sash member including a trunnion on the sash member, ratchet mechanism including a part mounted on the trunnion within the hollow rail, and a second part coacting with the first part and located in the hollow rail, and 40 manual means operable from the outside of the rail for operating the second part to hold it engaged with the first part and prevent ratcheting thereof.

JOHN F. LEVAN. 45
